LOCOMOTIVE FRONT END

Filed Sept. 14, 1942

FIG. 1.

FIG. 2.

Inventor
Gust J. Christenson
by *Arthur M. Hebron* Atty.

UNITED STATES PATENT OFFICE

2,356,217

LOCOMOTIVE FRONT END

Gust J. Christenson, Chicago, Ill., assignor to
Locomotive Firebox Company, Chicago, Ill., a
corporation of Delaware

Application September 14, 1942, Serial No. 458,227

12 Claims.

(Cl. 230—97)

This invention relates to improvements in locomotive front ends and it consists of the matters hereinafter described and more particularly pointed out in the appended claims. The invention is more especially concerned with front ends equipped with spark arresters having vanes or deflectors which impart a centrifugal or whirling action to the products of combustion (gases and cinders) before they are discharged through the stack with the exhaust steam from the nozzle in the front end. Spark arresters of this type are more efficient in their spark arresting action than those which employ a woven wire screen or netting for spark arresting purposes. In the latter type of spark arresters, the screen or netting soon becomes cinder cut so as to permit the discharge of sparks from the stack and such arresters require frequent patching or renewal of the screen or netting.

However, spark arresters which induce the centrifugal or whirling action to the products of combustion have a tendency to cause a more rapid wear in the lift pipe or stack so that the periods of usefulness of the same is much reduced. The wear mentioned is produced by cinders entering the lift pipe and stack with a whirling motion due to centrifugal force of the carrier gases. This action compels the cinders to hug the internal surface of the lift pipe and stack and makes their path of travel considerably longer because of the whirling or spiraling action and which produces the wear mentioned.

Engine crews of locomotives equipped with spark arresters of this kind object to the fine cinders discharged from the stack, entering the cab and which is caused by the factors mentioned above. The reason is that some of the fine cinders tend to discharge from the stack in a more or less horizontal direction due to the centrifugal action in the arrester and stack assembly. The centrifugal or whirling action of the cinders at the top of the stack prevents the finer cinders from being lifted high enough above the stack to escape from being blown back toward and into the cab.

One of the objects of the invention is to provide a centrifugal spark arrester equipped front end wherein the products of combustion entering the lift pipe and stack from the arrester, are subjected to a reversal of flow so that they are discharged up through and out of the stack with a substantially non-whirling action.

Another of the objects of the invention is to provide a locomotive front end of the kind just above mentioned wherein the products of com-

bustion entering the lift pipe and stack are directed inwardly away from the internal surface thereof to pass up through the same with the exhaust steam discharged by the associated nozzle.

Also, another object of the invention is to provide a front end that includes parts which reduce the cinder cutting and wearing action on the lift pipe and stack.

10 A further object of the invention is to provide a front end structure which insures a substantially complete extinguishment of such live sparks that might pass through the arrester and at the same time will throw the cinders inwardly toward the exhaust steam discharged into the lift pipe and stack to be ejected so high above the cab that they are not blown back thereinto.

Again, it is an object of the invention to provide a device which may be applied to centrifugal spark arrester equipped locomotives already in service with but a small amount of expense and which device will reduce to a minimum the cinder cutting action and wear which such an arrester induces in the lift pipe and stack.

15 25 The above mentioned objects of the invention, as well as others together with the advantages thereof will more fully appear as the specification proceeds.

In the drawing:

30 Fig. 1 is a longitudinal vertical sectional view through a locomotive front end embodying the preferred form of the invention.

Fig. 2 is a horizontal sectional view through the same, on an enlarged scale, as taken on the line 2—2 of Fig. 1.

35 Referring now in detail to that embodiment of the invention illustrated in the drawing, 5 indicates the tubular body of a locomotive smoke box shell, which is connected at its rear end to the front end of the boiler shell 6 of the locomotive in any suitable manner. The interior of the smoke box shell is separated from the water space of the boiler shell by a flue sheet 7. The front ends of flues 8 are secured in the flue sheet so as to open and deliver into the smoke box shell the products of combustion from the firebox (not shown) of the locomotive. 9 indicates the front of the smoke box shell and which front includes a door 10 therein.

40 45 50 11 indicates the lift pipe which depends from the bottom end of the stack 12 a suitable distance downwardly into the smoke box shell.

13 indicates the exhaust stand or pipe which rises from the bottom of the smoke box shell in axial alignment with the lift pipe and stack. Said

stand or pipe is relatively low or short and carries at its top end an exhaust nozzle or tip 14 of any approved kind.

In the smoke box shell is located a centrifugal spark arrester of the so-called circumferentially open type and the same is indicated as a whole by the numeral 15. Such an arrester, which is cylindrical in shape, has its axis arranged in alignment with the axis of both the tip or nozzle 14 and the lift pipe 11. It comprises vertically spaced apart circular top and bottom plates 16 and 17 respectively and perpendicular vanes or deflector plates 18 fixed at their ends to said plates. The top plate 16 has a central opening 19 therein of one diameter, and the bottom plate 17 also has a central opening 20 therein of a smaller diameter to accommodate the exhaust tip or nozzle before mentioned, which is disposed within the arrester. The arrester structure before mentioned is fastened in position in the smoke box shell in any suitable manner and one manner will be mentioned later but the same forms no particular part of the invention. Therefore the same is neither shown nor described in detail.

In the present instance the deflector vanes or plates 18 of the arrester are disposed tangentially to the axis of the arrester as a whole and extend inwardly from the circle of the top and bottom plates thereof to terminate short of the circle of the opening 19 in the top plate.

As the products of combustion enter the smoke box shell from the flues 8, they are distributed about the open periphery of the arrester. This movement of the products of combustion is produced by the draft action of the exhaust steam jet discharged from the nozzle or tip 14 and which action causes an entrainment of said products up through the lift pipe and stack for discharge to the atmosphere. As said products pass through the channels or passageways between the vanes or deflector plates 18, a whirling or centrifugal action is imparted to said products as they enter the lift pipe 11 and stack 12 and which action, if not counteracted, causes said products to impinge against the internal surface of said lift pipe and stack and cinder cut and produce wear therein.

To prevent the cinder cutting and wear of said lift pipe and stack, I interpose between said lift pipe and said arrester a structure which counteracts the whirling action of the products of combustion and causes them to be directed inwardly away from the internal surfaces thereof into the path of the exhaust steam passing up the stack and such means, which is indicated as a whole at 21 in Fig. 1, is as follows:

22 and 23 indicate the top and bottom vertically spaced circular rings of said means. Said rings, as shown herein, are of like diameter and which diameter approximates that of the lift pipe and the opening 19 in the top plate 16 of the arrester so that the top ring may be passed through said opening from below. These rings are held in their spaced relation by means of a plurality of vertically disposed vanes or deflector plates 24 which are welded or otherwise secured in edge to edge relation thereto. Said vanes or plates are disposed tangentially to the axis of the rings 22-23, but face in a direction opposed to that of the deflector plates or vanes 18 of the spark arrester. The diameter of the circle of the outer edges of the vanes 24 is somewhat larger than that of the opening 19 in the top plate of the deflector. The total area of the

openings or passageways between the vanes 24-24 is smaller than that of the area under the lift pipe and a relative proportion between these areas, of about 1 to 3 has given good results.

The top ring 22 is provided with an outwardly extending radial portion or flange 25 which is disposed a short distance below the top plate of the arrester and therefore all of the vanes 24 are entirely within the upper portion of the arrester 15. Bolts 26 pass up through the flange 25, top plate 16 of the arrester, as well as through the horizontal flange 27 (see Fig. 1) of an angle bar ring on the bottom end of the lift pipe, so that nuts 28 may be applied to the top end of said bolts properly to hold the assembly together. It is pointed out that in tightening up the nuts 28 on the bolts 26, the top edge of the top ring 22 is drawn into a tight fitting engagement with the bottom edge of the lift pipe as appears in Fig. 1.

By reason of the opposed direction of the vanes 24 with respect to the direction of the vanes 18 of the arrester 15, said vanes 24 counteract the whirling action of the products of combustion as they enter the channels or spaces therebetween from the interior of the arrester and directs them, and more particularly the cinders, away from the internal surface of the lift pipe and stack, into the column of exhaust steam discharged into the lift pipe and stack by the nozzle or tip 14. The vanes 24 also assist in extinguishing such sparks as may impinge thereagainst. Thus but a small part of the products of combustion and cinders, if any at all, are permitted to engage said internal surface so that wear thereof, due to cinder cutting action is reduced to a minimum. Furthermore, because of the counter directional action of the vanes 24, the products as they enter the stack move more nearly as a non-whirling stream. Also, it is pointed out as the products of combustion are directed into the column of exhaust steam, and are not whirling rapidly if at all, they are propelled or lifted so high above the top end of the stack 12 that they clear the cab entirely when blown back by the wind stream action of the locomotive while under way.

In locomotives in service and equipped with the spark arrester 15 described, the bolts 26 and nuts 27 are employed to support the arrester from the lift pipe 11. One way to install the means 21 in such a locomotive is as follows: the bolts 26 are removed and a sufficient number of vanes 18 are removed from the front of the arrester, after the removal of the front 9 from the smoke box shell. The means 21 as a unitary structure is entered into the front of the arrester and is positioned in place and the bolts and nuts replaced and tightened up as before mentioned. The vanes 18 removed from the arrester are restored and the front 9 is then reapplied to the smoke box shell.

The construction described is simple and inexpensive and is indeed efficient in reducing to a minimum the wear on the lift pipe and stack and the blowing back of fine cinders into the cab.

While in describing my invention I have referred in detail to the form, arrangement and construction of the parts involved, the same is to be considered only in the illustrative sense so that I do not wish to be limited thereto except as may be specifically set forth in the appended claims.

I claim as my invention:

1. In combination with a smoke box, a smoke

stack having a bottom end portion disposed in the smoke box, a nozzle arranged to discharge exhaust steam into said smoke stack portion, means in said smoke box for imparting a whirling action in one direction to the products of combustion entering the same under the action of the exhaust steam discharged by the nozzle, and means associated with said bottom end portion of the stack for counteracting said whirling action of said products of combustion as they enter said bottom end portion of the stack by effecting reversal of flow of at least a part of said products of combustion, thereby causing the products of combustion discharging up through the stack to move as a substantially non-whirling stream.

2. In combination with a smoke box, a smoke stack having a bottom end portion disposed in the smoke box, a nozzle arranged to discharge exhaust steam into said smoke stack portion, means in said smoke box for imparting a whirling action in one direction to the products of combustion entering the same under the action of the exhaust steam discharged by the nozzle, and means associated with said bottom end portion of the stack and including a plurality of vanes for counteracting said whirling action of said products of combustion as they enter said bottom end portion of the stack by effecting a reversal of flow of at least a part of said products of combustion, thereby causing the products of combustion discharging up through the stack to move as a substantially non-whirling stream.

3. In combination with a smoke box, a smoke stack having a bottom end portion disposed in the smoke box, a nozzle arranged to discharge exhaust steam into said smoke stack portion, means in said smoke box and including a plurality of vanes which face in one direction for imparting a whirling action in said one direction to the products of combustion entering the same under the action of the exhaust steam discharged by the nozzle, and means associated with said bottom end portion of the stack for counteracting said whirling action of said products of combustion as they enter said bottom end portion of the stack by effecting reversal of flow of at least part of said products of combustion, thereby causing the products of combustion discharging up through the stack to move as a substantially non-whirling stream.

4. In combination with a smoke box, a smoke stack having a bottom end portion disposed in the smoke box, a nozzle arranged to discharge exhaust steam into said smoke stack portion, means in said smoke box and including a plurality of vanes which face in one direction for imparting a whirling action in said one direction to the products of combustion entering the same under the action of the exhaust steam discharged by the nozzle, and means associated with said bottom end portion of the stack and including vanes arranged to counteract said whirling action of said products of combustion as they enter said bottom end portion of the stack by effecting reversal of flow of at least a part of said products of combustion, thereby causing the products of combustion discharging up through the stack to move as a substantially non-whirling stream.

5. In combination with a smoke box, a smoke stack having a bottom end portion disposed in the smoke box, a nozzle arranged to discharge exhaust steam into said smoke stack portion, means in said smoke box for imparting a whirling action in one direction to the products of combustion entering the same under the action of

the exhaust steam discharged by said nozzle, and means associated with said bottom end portion of the stack and disposed at least in part in said first mentioned means for counteracting said whirling action of said products of combustion as they enter said bottom end portion of the stack and for directing them inwardly away from the internal surface of the stack for passage up through the same with the exhaust steam discharged into the stack by said nozzle.

6. In combination with a smoke box, a smoke stack having a bottom end portion disposed in the smoke box, a nozzle arranged to discharge exhaust steam into said smoke stack portion, means in said smoke box for imparting a whirling action in one direction to the products of combustion entering the same under the action of the exhaust steam discharged by said nozzle, and means associated with the bottom end of the stack and disposed at least in part in the first mentioned means and including a plurality of vanes for counteracting said whirling action of said products of combustion as they enter said bottom end portion of the stack and for directing them inwardly away from the internal surface of the stack for passage up through the same with the exhaust steam discharged into the stack by said nozzle.

7. In combination with a smoke box, a smoke stack having a bottom end portion disposed in the smoke box, a nozzle arranged to discharge exhaust steam into said smoke stack portion, means in said smoke box and including a plurality of vanes which face in one direction for imparting a whirling action in said one direction to the products of combustion entering the same under the action of the exhaust steam discharged by said nozzle, and means associated with said bottom end portion of the stack and disposed at least in part in the first mentioned means, for counteracting the whirling action of combustion as they enter said bottom end portion of the stack and for directing them inwardly away from the internal surface of the stack for passage up through the same with the exhaust steam discharged by said nozzle.

8. In combination with a smoke box, a smoke stack having a bottom end portion disposed in the smoke box, a nozzle arranged to discharge exhaust steam into said smoke stack portion, means in said smoke box and including a plurality of vanes which face in one direction for imparting a whirling action in said one direction to the products of combustion entering the same under the action of the exhaust steam discharged by said nozzle, and means associated with said bottom end portion of the stack and disposed at least in part in the first mentioned means, and including vanes arranged to counteract the whirling action of said products of combustion as they enter said bottom end portion of the stack and to direct them inwardly away from the internal surface of the stack for passage up through the same with the exhaust steam discharged by said nozzle.

9. In combination with a smoke box, a smoke stack having a bottom end portion disposed in the smoke box, a nozzle arranged to discharge exhaust steam into said smoke stack portion, means in said smoke box for imparting a whirling action in one direction to the products of combustion entering the same under the action of the exhaust steam discharged by said nozzle, and means associated with the bottom end portion of the stack and including a plurality of vanes disposed entirely within the upper portion of

the first mentioned means for counteracting said whirling action of said products of combustion as they enter said bottom end portion of the stack and for directing them inwardly away from the internal surface of the stack for passage up through the same with the exhaust steam discharged into the stack by said nozzle.

10. In combination with a smoke box, a smoke stack having a bottom end portion disposed in the smoke box, a nozzle arranged to discharge exhaust steam into said smoke stack portion, means in said smoke box providing a circumferentially open spark arrester that includes top and bottom walls and a plurality of vanes extending between said walls for imparting a whirling action in one direction to the products of combustion entering said arrester between said vanes under the action of the exhaust steam discharged by said nozzle, and means having a portion disposed in said spark arrester and another portion in communication with said bottom end portion of the smoke stack for counteracting said whirling action of said products of combustion as they enter said portion of the stack and for directing them inwardly and away from the internal surface of the stack for passage up through the same with exhaust steam discharged into the stack by said nozzle.

11. In combination with a smoke box, a smoke stack having a bottom end portion disposed in the smoke box, a nozzle arranged to discharge exhaust steam into said smoke stack portion, means in said smoke box for imparting a whirling action in one direction to the products of combustion entering the same under the action of the exhaust steam discharged by said nozzle, and

means including top and bottom rings and vanes extending therebetween, said top ring communicating with said bottom end portion of the stack and said bottom ring and vanes being disposed within said first mentioned means and operating to counteract the whirling action of said products of combustion as they enter said bottom end portion of the stack and to direct them inwardly away from the internal surface of the stack for passage up through the same with the exhaust steam discharged into the stack by said nozzle.

12. In combination with a smoke box, a smoke stack having a bottom end portion disposed in the smoke box, a nozzle arranged to discharge exhaust steam into said smoke stack portion, means in said smoke box providing a circumferentially open spark arrester that includes top and bottom walls and a plurality of vanes extending between said walls for imparting a whirling action in one direction to the products of combustion entering said arrester between said vanes under the action of the exhaust steam discharged by said nozzle, and means associated with said bottom end portion of the stack and said first mentioned means respectively and including a top ring in direct communication with said portion of the stack and a plurality of vanes extending downwardly from the ring and disposed entirely within said first mentioned means for counteracting said whirling action of said products of combustion and for directing them inwardly away from the internal surface of the stack for passage up through the same with the exhaust steam discharged into the stack by said nozzle.

35

GUST J. CHRISTENSON.
